UNITED STATES PATENT OFFICE.

VICTOR W. THOMAS, OF WAUKEGAN, ILLINOIS.

CURRENT-COLLECTOR FOR MAGNETOS.

1,372,788.

Specification of Letters Patent. Patented Mar. 29, 1921.

Application filed April 5, 1919. Serial No. 287,823.

To all whom it may concern:

Be it known that I, VICTOR W. THOMAS, a citizen of the United States, and a resident of Waukegan, in the county of Lake 5 and State of Illinois, have invented certain new and useful Improvements in Current Collectors for Magnetos, of which the following is a specification.

My present invention has relation to the 10 provision of instrumentalities for the conservation of the current not utilized in ignition or illumination, which is generated by the magneto in the operation of an internal combustion engine. As will be here- 15 after seen, the present embodiment of my invention is especially designed for application to Ford automobiles, although the principles and general arrangement of parts employed, with slight changes of structural 20 details, are applicable in most cases in which magnetos are used for generating current for ignition in connection with the operation of internal combustion engines.

In Ford automobiles, as they are at present sold, electricity for both ignition and lighting is generated by a magneto which is partially built into the fly-wheel of the engine and which consists of a series of oppositely wound bundles of wire disposed in 25 the field of an equal number of pairs of fixed magnets mounted upon and rotatable with the fly-wheel. The polarity presented to the field by each magnet of a pair is the same, but the polarity of adjacent 30 pairs of magnets differ, and the passage of the fields of the series of pairs of magnets of opposite polarity through the series of oppositely wound bundles of wire produces or generates an alternating current of con- 35 siderable volume. The volume of this current is considerably greater than is necessary for purposes of ignition, and notwithstanding the production of a large excess current at times, there is no current at all 40 for purposes of lighting when the engine is not running.

The principal object of my present invention is the provision of a simple and inexpensive attachment which will collect the 45 electrical energy generated by a magneto in the form of a direct current whereby that

portion of the energy not utilized in ignition or illumination may be passed into a storage battery and conserved for use at a time when it is desired to employ the current without running the motor. It will also hereafter be seen that an important detail in the practical working out of the instrumentalities for obtaining the object above outlined is the nicety of timing of the 55 movements of the fixed magnets and the commutator for taking off the current. A further object of my invention is therefore the provision of means for adjusting the relation of the movement of the crank- 60 shaft of the engine, which rotates the fixed magnets, with the movement of the timing shaft of the engine, which I employ for operating the commutator. It will also be seen that this same means may be advan- 65 tageously utilized in securing the adjustment of the time of ignition, even where my commutator is not employed.

I attain the above objects by means of the mechanism illustrated in the accompanying 70 drawing, in which,

Figure 1 is a front elevation of the forward end or cover of the timing-gears box, with the brackets for supporting the commutator and its associated parts cast in- 75 tegral therewith;

Fig. 2 is a vertical central section of the structure shown in Fig. 1;

Fig. 3 is a fragmental section through the commutator taken on line 3-3, Fig. 2;

Figs. 4 and 5 are circuit diagrams;

Fig. 6 is a fragmental detail of the assembly of the spiral gear with the timer shaft.

In the drawing I have employed the same 80 reference characters to designate similar portions throughout the several views.

My entire mechanism is mounted upon the forward end or cover of the timing gears case, and in order to install it all that is 85 necessary is to dismount the cover for the timing gears case, which comes with the car, and substitute therefor the structure hereafter described and illustrated.

Through the central opening 10 in the 90 forward end or cover, 11, of the timing-gears box extends the shaft, 12, upon which

is normally mounted the distributor mechanism by means of a slotted collar, a pin, 13, extending in the shaft, 12, and held in place by the flanged washer or cap 15, and nut, 16. The slotted collar of the original distributing mechanism is removed and there is mounted upon the shaft, 12, in place thereof a spiral gear, 17, having a slotted central flange or hub, 18, adapted to be secured to the shaft, 12, by the pin, 13, flanged washer or cap, 15, and nut, 16, in the same manner as the collar of the original distributor was secured thereto. Immediately to one side of the central opening, 10, and respectively above and below the same, are integral forward extensions from the cover, 11. These extensions or pillow blocks, 18, and 19, are vertically bored and tapped to receive the exteriorly threaded bushings, 20 and 21. Extending forwardly from the face of the cover plate, 11, above the pillow blocks, 18 and 19, are the commutator bracket and box, 22 and 23, which box is centrally bored at 24, to align with the bores in the bushings, 20 and 21. Mounted to rotate in and extending upwardly from the bushings, 20 and 21, is a shaft, 25, which is longitudinally slotted at 26 between the bushings, 20 and 21, and to which is slidably secured by means of a key or spline, 27, a spiral gear, 28, which meshes with the spiral gear, 17. Between the lower side of the spiral gear, 28, and the lower bushing, 21, I preferably provide a fiber thrust collar, 29. It will now be seen that by screwing the bushings 20 and 21 both up or both down, I can elevate or depress the spiral gear 28, and as the gear 28 is splined or keyed to the vertical shaft 25, and is in mesh with the spiral gear, 17, its movement up or down, without a movement of the gear, 17, will cause a rotation of the gear 28 and the shaft 25, thereby providing a simple and extremely delicate means for adjusting the movement of the vertical shaft, 25, to the movement of the motor or engine which moves the shaft, 12, through suitable gear trains. After the bushings 20 and 21 have been adjusted, they may be secured in these desired positions by means of the lock-washers 30 that screw upon said bushings against the pillow-blocks 18 and 19, respectively.

The shaft 25 is continued upwardly above the commutator-box 23, the upper extension above the commutator-box being conveniently employed for mounting the timer and distributor to be hereinafter described. The top of the side walls of the commutator-box 23 is interiorly bored to provide the annular shoulder 31, and the shaft 25 is preferably reduced to provide a shoulder 32. A centrally bored plate 33 through which the reduced portion of the shaft extends rests upon the shoulder 31 and acts as a closure

for the commutator-box and as a base for the timer structure to be hereinafter described.

Within the commutator-box 23 and below the plate 33 upon the shaft 25 is mounted the commutator, which may be constructed in any desired manner, but which may conveniently be made of a central disk-shaped block 34 of insulating material which is surrounded with the upper and lower caps 35 and 36, respectively. The vertical cylindrical flanges of these caps are castellated and dove-tailed, but not contacting, to form, respectively, downwardly and upwardly extending, parallel contact members 37 and 38, the spaces between which members being preferably filled with a suitable insulating material 39.

The Ford magneto is constructed with sixteen pairs of magnets and sixteen coils, but, as the timing shaft through which my shaft 25 is actuated, rotates at but one-half the speed of the engine crank-shaft with which the magnets rotate, my commutator is constructed with thirty-two of the contact members 37 and 38.

From preferably quadrantal portions of the commutator-box 23, extend two stub embossments 40, which are bored to provide brush-chambers 41, having annular shoulders 42 at their outer ends. These chambers 41 are lined with insulating shells 43, in which are mounted carbon brushes 44 pressed toward the commutator by coiled springs 45 and are electrically connected through the springs 45 to the outside circuit by means of screws 46 in connection with insulating washers 47 and binding-nuts 48. The brushes 45 are so positioned that when one brush is contacting a downwardly extending contact surface 37, the other will be engaging an upwardly extending contact surface 38.

Extending from the bottom of the commutator-box 23 is a stub embossment 49 similar in all respects to the stub embossments 40, and similarly provided with insulation 50 and a carbon contact brush 51. This brush 51 contacts the lower face of the lower cap 35 and is in electrical communication with all the upstanding contact surfaces 38. The brush 51 is in electrical communication through its binding-post 52 with the insulated end 53 of the magneto circuit 54, while the upper cap 36 of the commutator is extended to the shaft 25 and is thereby in electrical connection with the grounded end 55 of the magneto circuit 54. The binding-posts 46 of the brushes 45 are connected in circuit with respectively the positive and negative posts 56 and 57 of a storage battery.

In diagrammatic Fig. 4 it is assumed that the magneto is in a positive phase of its operation in which positive current is being

delivered to the under or bottom cap 35. Positive current is therefore passing from the brush 45 in contact therewith to the positive pole 56 of the storage battery, while the 5 grounded or negative end of the current is in connection with the negative pole 54 of the storage battery through the upper cap 36 of the commutator. Fig. 5 illustrates the next succeeding phase of current production 10 in which negative current is passing from the insulated end of the magneto circuit 53 to the lower commutator cap 35 and positive current is in the grounded circuit 55 from the magneto which is connected 15 with the upper cap 36 of the commutator, but as will be seen from Fig. 5 during this phase of current production, the upper cap 36 of the commutator is in electrical connection with the positive pole 56 of the storage 20 battery and the lower cap of the commutator is in electrical connection with the negative pole 57 of the storage battery. The requisite nicety of timing between the movement of the magneto and the commutator is secured, 25 as heretofore pointed out, by the adjustment of the bushings 20 and 21.

Fitting into the top of the commutator-box 23, and resting upon the top of the plate 33, is a timer and distributor shell 58, 30 which is adapted to be held in position by a spring-clip 59 carried by a bracket 60, preferably cast integral with the commutator-box 23. The timer and distributor structure employed may be of any form but prefer- 35 ably of the construction shown in my application for Letters Patent of the United States for distributor and timer structure, ex- 40 ecuted even date herewith and filed April 5th, 1919, Serial Number 287,824. The mov- 45 ing wiper 60 element of such a timer is mounted upon and secured to the upper end of the shaft 25, which extends above the plate 33 and into the timer and distributor shell 58. The mechanism by which this as- 50 sembly is made is similar to and identical with the instrumentalities for securing the spiral gear 17 to the timer shaft 12, as heretofore described and as illustrated in Fig. 6. In the installation of the timer and dis- 55 tributor directly with the timer shaft 12, it often happens that a proper synchronization of the movement of the timer with the piston movement of the engine is not secured, but in the installation of the distributor and 60 timer, as herein described, through the instrumentalities of the spiral gears 17 and 28, which permits of an extreme delicacy of adjustment through the medium of the bushings 20 and 21, the proper relation between the movement of the timer and the piston can be easily secured.

Having described my invention, what I claim as new is:—

1. In combination with an internal com- 65 bustion engine and an electrical generating

mechanism secured to and driven by the crank-shaft thereof, a commutator for tak- 7 ing current from said generator, and adjust- 7 able means for operatively connecting 7 said commutator with the timing shaft of 7 said engine comprising a spiral gear secured to said timing shaft, a shaft upon which 7 said commutator is secured, a spiral gear mounted upon and longitudinally movable 7 of said commutator shaft, and means for 7 securing the same in desired co-operative relation with said first-mentioned spiral gear.

2. In combination with an internal com- 8 bustion engine and an electrical generating 80 mechanism secured to and driven by the crank-shaft thereof, a commutator for tak- 8 ing current from said generator, and adjust- 8 able means for operatively connecting said 85 commutator with the timing shaft of said engine comprising a spiral gear secured to 85 said timing shaft, a shaft upon which said 90 commutator is secured, a spiral gear mounted upon and longitudinally movable of said 90 commutator shaft and in mesh with said 95 first-mentioned spiral gear, and devices for 95 adjusting said spiral gear longitudinally upon said commutator shaft.

3. An attachment for an internal com- 95 bustion engine having a timer-shaft com- 95 prising a spiral gear adapted to be assem- 100 bled with said timer shaft, a driven shaft, a second spiral gear longitudinally movable 100 of said driven shaft and in mesh with said first-mentioned gear, threaded bushings for 105 said driven shaft disposed on opposite sides 105 of said gear and adapted to control the posi- 110 tion of said gear upon said shaft, and com- 110 mutator and timer and distributor mech- 115 anism secured to and actuated by said driven 115 shaft.

4. An attachment for an internal combus- 110 tion engine having a timer shaft, of a spiral 110 gear adapted to be mounted on said timer 115 shaft, a driven shaft, a second spiral gear 115 longitudinally movable with respect to said 120 driven shaft and in mesh with said first 120 mentioned gear, means for moving said 125 second spiral gear to and securing it at a desired longitudinal position upon said 125 driven shaft, said means consisting of 130 threaded bushings surrounding said driven 130 shaft upon opposite sides of said second 130 spiral gear whereby the movement of said 130 bushings adjusts and secures in position said 130 second spiral gear, and current control de- 130 vices coactively mounted with respect to 130 said driven shaft.

5. An attachment for internal combustion engine having a timer shaft, of a driven 125 shaft, internmeshing spiral gears mounted 125 respectively upon said timer and driven 130 shafts, means for moving and securing one 130 of said gears longitudinally of its mount- 130 ing comprising bushings forming journals 130

for the shaft carrying the movable gear; said bushings being disposed upon opposite sides of said movable gear whereby their movement changes the position of said movable gear and current control devices coaxially mounted with respect to said driven shaft.

Signed at Waukegan, county of Lake and State of Illinois, this 29th day of March, 1919.

VICTOR W. THOMAS.
